UNITED STATES PATENT OFFICE.

SIGURD E. ANDERSON, OF DES MOINES, IOWA.

CEMENT-STAVE MACHINE.

1,346,779.

Specification of Letters Patent. Patented July 13, 1920.

Application filed September 15, 1919. Serial No. 323,982.

To all whom it may concern:

Be it known that I, SIGURD E. ANDERSON, a citizen of the United States, and resident of Des Moines, in the county of Polk and State of Iowa, have invented a certain new and useful Cement-Stave Machine, of which the following is a specification.

The object of my invention is to provide a cement stave machine of simple, durable and inexpensive construction.

More particularly it is my object to provide a machine of the class described adapted to be used in connection with a tamping machine, wherein means are provided for holding the parts of the molds rigid to prevent the impact of the tampers from moving said parts to vary the size of the staves formed.

A further object is to provide a cement stave machine provided with movable mold members, whereby the stave may be formed and the mold members then moved to position away from the stave to permit ready removal of the stave.

Still a further object is to provide a machine having a pallet designed to be held in horizontal position when the stave is being formed, and adapted to be moved to inclined position when the mold members are separated for releasing the stave, whereby the pallet and the stave may be readily slid off its supporting platform onto a truck or other means for carrying the stave to a storage room.

Still a further object of my invention is to provide mold members designed to form the sides of the stave, which are so arranged that after the stave has been formed said members may be slid along the side of the stave to trowel the edges thereof before the members are separated to permit the removal of the stave.

Still a further object is to provide a pallet supporting platform comprising spaced angle irons which are pivoted to the rear upper portion of the machine frame, and means for swinging the forward ends of the angle irons from horizontal to inclined position, said means being so arranged that they form a direct connection between the angle irons and the foundation upon which the frame rests at the time that the stave is being formed.

Still a further object is to provide a flexible brace extended across the lower part of the frame, to which levers or other movable devices may be secured to move the

pallet supporting platform from horizontal to inclined position, or vice versa, so that the impact of tamping devices on the cement in the mold will be transmitted direct to the foundation to thereby eliminate unnecessary vibration of the frame parts and to prevent bending of the frame parts, which would cause variation in the size of the staves formed.

In this connection it may be mentioned that the staves formed by these machines are approximately ten inches across, and are used to form the circular walls of silos varying from twelve to eighteen feet in diameter, so that variation in size amounting to a very small fraction of an inch in each stave will amount to a variation of one or more inches in the completed structure. Concrete or cement staves are readily cracked by shearing stresses, so that it is important that there shall be no variation in the position of the staves in the various tiers in the wall, or the hoops which hold the staves in place are very likely to cause a shearing stress and thereby crack or break the cement of the staves.

The parts of my improved machine are therefore designed to form staves with substantially no variation in size, and at the same time are designed to withstand the stresses and strains caused by the impact of tamping devices which are used when the stave is being formed.

It is also necessary that these staves be made in large quantities in order to make the product commercially successful, so that means must be provided for readily removing the staves from the machine after they have been formed.

To solve these problems my machine is provided with positive means for locking and centering the mold members by which the ends and sides of the staves are formed, in addition to the means for moving the mold members to proper position for forming the staves and to position spaced from each other for the removal of the staves. Toggle levers are also extended between the pallet supporting platform and the foundation upon which the frame rests, and are so arranged that the pivots of the toggle levers are in vertical alinement when the pallet is in position for forming staves, so that the impact of a tamping device is carried in straight lines down to the foundation upon which the frame rests.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of my improved machine in which parts are broken away to better illustrate the construction.

Fig. 2 is an end elevation of the machine.

Fig. 3 is a front view of the machine.

Fig. 4 is an enlarged elevation showing in detail the operation of the locking device for holding the mold members from movement when the stave is being formed.

Fig. 5 is a top or plan view of the mold members when they are moved away from each other to permit removal of the stave.

Fig. 6 is a perspective view of the stave formed by the machine; and

Fig. 7 is an enlarged, detail view of the means for adjusting the relative vertical position of the rear end of the pallet supporting platform.

Referring to the accompanying drawings I have used the reference numeral 10 to indicate generally the four vertical angle irons forming the corners of the frame of my machine, and the numeral 11 to indicate the horizontal angle irons forming the front and rear top members of my frame. Angle irons 12 form the side top members of my frame, and the structure just described is supported by transverse horizontal and diagonal brace members 13 and 14.

Resting on the side members 12 are mold members 15 and 16, which are designed to form the sides of the stave made by this machine. Extending from the members 15 and 16 are end mold members 17 and 18, designed to form the ends of the stave.

Intermediate of the members 15 and 16 levers 19 and 20 are pivoted to the frame members 12 and are provided with elongated slots at each end, designed to receive pins 21 extended through the members 15 and 16. At the outer edges of the members 15 and 16 rollers 22 are pivotally mounted on vertical pins 23 which will hereinafter be more fully described, and designed to coact with the edges of the members 15 and 16 to govern the direction of their movement caused by the levers 19 and 20. Springs 24 hold the members 15 and 16 yieldingly in engagement with the rollers 22 to insure normally a yielding contact therewith.

From the description of the parts hereinbefore mentioned it will be seen that rotation of the levers 19 and 20 upon their pivots would normally cause the members 15 and 16 to move toward or from each other in an arcuate path. The outer edges of the members 15 and 16 which contact with the rollers

22 are, however, so arranged that the straight portion 25 causes the members 15 and 16 to move in lines parallel with each other during the first part of the movement of the levers 19 and 20 when the parts are in the position shown in Fig. 1. As the rollers run off from the straight portion 25 they strike the curved portions 26, thereby permitting the mold members to move substantially in the arcuate path that they would follow if pivoted to the levers 19. The straight portions 25 and the curved portions 26 will be hereinafter referred to as cam faces.

Thus when a stave has been formed between the mold members when they are in the position illustrated in Fig. 1, the members 15 and 16 will first be slid along the edges of the stave to permit the removal thereof. As the mold members forming the ends of the stave move with the members 15 and 16, they are also moved away from the stave to permit its removal.

The following means are provided for operating the levers 19 and 20.

A lug 27 extends from the lever 20 and is pivotally secured to a link 28. A lug 29 extends from the frame member 12 and pivotally supports a forwardly extending lever 30 at 31. The link 28 is also pivotally connected to the lever 30, whereby swinging of the lever 30 on the pivot 31 causes a like swinging of the levers 19 and 20, to thereby operate the mold members 15, 16, 17 and 18. A latch device 32 is extended from the frame member 12 to support and hold the lever 30 in position when the mold members are arranged for forming the stave.

Secured to the rear mold members 15 is a rearwardly extending plate 33 which slidably rests on supporting rods or strips 34 and 35. The plate 33 extends to position adjacent to the rear portion of the frame of the machine.

Slidably mounted on the plate 33 is a bottomless hopper member 36, which may be reciprocated from front to rear of the machine by means of the lever 37 and links 38.

From the description of the parts just mentioned it will be seen that stave-forming material may be poured into the hopper 36 and held therein by means of the plate 33. When it is designed to form a stave the hopper 36 is moved by means of the lever 37 to the position shown in full lines in Fig. 2, which will permit the material in the hopper to run down between the mold members, and then the hopper may be moved rearwardly to the position shown by the dotted lines in Fig. 2, which will cause the forward inner edge of the hopper to remove any surplus material above the mold members 15 and 16, thereby leaving the proper quantity of stave material between the mold members. The plate 33 is of such size that

the movement of the mold member 15 to any of its positions will not move the plate out from under the hopper to thereby allow its contents to escape.

5 A strip of metal 39 or other suitable material is supported above the frame members 12 by means of the pins 23, in position to prevent vertical play of the mold members 15 and 16 to form a guide member adapted 10 to coact with extending lugs 40 on the hopper 36.

Secured to the strip 39 adjacent to the mold members is an angle iron having a vertical flange 40 and a horizontal flange 42. 15 A pair of levers 43 are pivoted at 44, intermediate of their ends, to the vertical web 41 of the angle iron.

At the outer end of the levers 43 are fixtures 45 having a transverse central slot in 20 the upper opening thereof, whereby upwardly extending spaced ears are formed, between which are pivotally received the ends of the levers 43. The fixtures 45 have a downwardly extending pin 46 which is 25 provided with a tapered end designed to enter a corresponding opening in the mold members 15 and 16.

Alined openings are provided in the horizontal web 42 of the angle iron and the 30 strip 39, to provide a guideway for the reciprocation of the pin 46, so that movement of the tapered end of the pin into the opening in the mold members may both tend to properly position the mold members and to 35 lock them from further movement.

A lever 47 is provided with a laterally extending pivot 48 designed to be somewhat loosely received in openings in the adjacent ends of the levers 43 and to extend 40 to position adjacent to the horizontal web 42 of the angle iron. The last described end of the lever is provided with a rounded edge or cam surface 49, which is designed to coact with the web 42, so that rotation of the 45 lever on the pivot 48 will tend to raise the adjacent ends of the levers 43 to thereby push the outer ends downwardly, which will force the pins 46 into the openings in the mold members.

50 A pin 50 is secured to the vertical web 41 of the angle iron, in the path of the lower end of the lever 47, so that movement of the lever 47 to the right from the position shown in Fig. 4 will cause the lower end of 55 the lever to contact with the pin 50 to thereby lower the inner ends of the levers 43 to raise the pins 46 out of the mold members.

The parts just described are made to fit closely enough so that the frictional engagement of the various pins and levers is 60 sufficient to hold the outer ends of the levers 43 in their raised position when the lever 47 is swung to the right.

I provide the following means for supporting the pallet beneath the mold mem-

bers and for moving the pallet to inclined position to permit ready removal of the stave and pallet from the machine.

Secured to the rear transverse frame member 11 by means of bolts 51 is a bracket 70 52 having elongated slots 53 therein, designed to receive the bolts 51 and to thereby permit vertical adjustment of the position of the bracket.

Extending from the bracket 52 is a lug 54 75 having an opening therein through which is extended a horizontal bolt 55 designed to pivotally support a forwardly extending angle iron 56. A second angle iron 57 is similarly supported by the transverse frame 80 member 11 in position alined horizontally with the angle iron 56 and spaced therefrom.

For supporting the forward ends of the angle irons 56 and 57, and for swinging 85 them from horizontal to inclined position, I provide the following means.

A shaft 58 is pivoted between the front frame members 10 substantially midway between their tops and bottoms, and an upwardly extending lever 59 is secured thereto. Adjacent to the upper transverse frame member 11 a resilient latch device 60 is designed to coact with the lever 59 to hold it 90 in one of its adjusted positions. 95

A pair of toggle levers are extended between the angle irons 56 and 57 and the shaft 58. The lower lever of the toggle levers comprises a strap 61 fixed to the shaft 58 and extending upwardly therefrom and 100 provided with a transverse opening at its upper end designed to receive a bolt 62.

The upper member of the toggle levers comprises a U-shaped member 63, having alined openings in its ends, designed to receive the bolt 62, and an opening in its cross portion, designed to receive an upwardly extending bolt 64. 105

The bolt 64 may be adjusted relative to the member 63 by means of nuts 65 which are disposed at either side of the cross portion of the member 63. The upper portion of the bolt 64 is provided with an eye designed to receive a bolt 66 which is extended through the vertical web of the angle irons 110 56 and 57 to thereby form a pivotal connection between the upper toggle members and the angle irons. 115

From the construction of the parts just described it will be seen that rotation of 120 the rock shaft 58 by means of the lever 59 will cause the toggle levers 61 and 63 to move from the position in which they are alined vertically, as shown in Fig. 3, to the position in which they are shown by the 125 dotted lines in Fig. 2.

It will be noted that the toggle levers, when their pivots, comprising the rock shaft 58, the bolt 62 and the bolt 66, are alined vertically, support the angle irons 56 and 57 130

4
in their horizontal position or in position for making the cement stave.

It will thus be seen that the supporting and operating means for the angle irons 56 and 57 offer the greatest resistance to a downward blow on the pallets supported by the angle irons 56 and 57 when they are in position for forming the stave, and that the force of any such downward blow is carried by compression on vertical strips, so that there is little or no danger of the strips buckling.

This construction is of sufficient strength to support the pallet when the machine is being used without a tamping device, but where a tamping device is used it will be seen that, due to the indirect connection between the pallet and the foundation, considerable vibration of the frame will ensue unless the parts are made disproportionately heavy.

In order to overcome this difficulty I provide similarly arranged toggle levers comprising a lower member 67, and upper U-shaped member 68, and an adjustable bolt 69 similar in its arrangement to the bolt 64. The last described toggle levers are disposed directly beneath the central portion of the pallet when the pallet is in position for forming a stave, and extend from the angle irons 56 and 57 to a somewhat flexible strip 70 extended across the bottom of the machine frame. The last described strip is bent upwardly at its outer ends and secured in any suitable way to the cross brace 14. Upwardly extending ears 71 secured to the plate 70 support bolts 72 which form the pivot for the lower ends of the toggle members 67.

40 In order to operate the last described toggle members a link 73 is pivoted at one end to the bolt 62 and to a bolt 74 mounted in the members 68. On account of the variation in the radii of the arcs upon which the central pivots of the two pairs of levers travel, due to the difference in the length of the levers, very slight play is provided in the openings in the links 73, to compensate for the variations in the distance between the bolts 74 and 62 during the movement of the two pairs of toggle levers.

From the construction of the parts just described it will be seen that movement of the lever 59, together with the corresponding movement of the front toggle levers, simultaneously operates the rear toggle levers by means of the link 73.

60 Mounted on the angle irons 56 and 57 is a pallet stop 75, comprising a single strip of metal bent upon itself at 76 to form guides adapted to coöperate with bolts 77 in the horizontal webs of the angle irons to permit the stop 75 to be adjusted longitudinally relative to the angle irons. At 65 one end of the stop it is bent at 78 to form

a stop to prevent longitudinal movement of the pallet member when resting upon the angle irons.

In this connection it will be noted that when the machine is used for making staves 70 a comparatively large number of wooden pallets are sawed out of lumber of uniform thickness, and each stave made is formed on one of these pallets. After the stave is formed the angle irons are moved to the 75 position shown in dotted lines in Fig. 2, so that the pallet, together with the stave, may be readily slid off from the angle irons onto a truck or cart or any other convenient means for moving the staves to position 80 where they may be stored.

For this reason it is desirable to have the stop 75 made adjustable in order that pallet members may be readily positioned to bring the stave as near the center of the 85 pallet as is possible. Pallet members, however, are not usually furnished with the machine by the manufacturer, so that different men using these machines may make their pallets out of lumber of different thicknesses 90 so that adjustment of the relative vertical position of the angle irons must be provided for in order that the staves made may be of uniform thickness even though the thickness of the pallet blocks 95 may vary.

From the description of the parts heretofore mentioned, it will be seen that the brackets 52 may be adjusted vertically on the frame members 11, which will vary the relative vertical position of the rear angle irons 56 and 57. The bolts 64 and 69 are also arranged so that movement of the nuts thereon will vary the length of the upper toggle member to thereby vary the relative vertical 100 position of the forward ends of the angle irons.

In the practical operation of my improved machine, it will be seen that means are provided for insuring staves of uniform 11 size, and that the parts are so arranged as to require the least possible adjustment. Means are also provided so that the staves made by the machine will be of uniform thickness even though a tamper is used to 11 pack the concrete or cement in the molds.

In this connection it will be noted that I have provided two independent means for holding the mold members which form the ends and sides of the stave, from separating 12 during the stave forming operation, and I have provided a direct connection between the pallet supporting frame and the foundation, in order to minimize any tendency for the frame parts to buckle under the strain 13 of the tamping operation.

Some changes may be made in the construction and arrangement of the various parts of my improved cement stave machine without departing from the essential spirit 14

and purpose of my invention, and it is my intention to cover by my claims any modified forms of structure or use of mechanical equivalents which may be reasonably included within their scope.

I claim as my invention:

1. In a machine for making cement staves, a frame, mold members mounted thereon, adapted to form the sides and ends of the staves, means for moving the said mold members to position for forming the stave, and to position out of engagement with the formed stave, a pallet holding member, means for pivoting said member to the frame to permit said member to be moved selectively to horizontal position whereby a pallet thereon may coact with the mold members to form a stave, and to permit the ready removal of the pallet and stave, and means for supporting said member in horizontal position, adapted to form a rigid connection between the foundation on which the frame may rest and a portion of said member below the mold members.

2. In a machine for making concrete staves, comprising a foundation, a frame, and mold members mounted on the frame for forming the sides and ends of the staves, and movable selectively to position for forming the staves and to position to permit removing the staves, a pallet supporting platform, means for pivotally supporting the rear end of the platform on the frame, means for moving the platform selectively to horizontal position and to inclined position, and means for forming a rigid connection between the foundation and the platform when the latter is in horizontal position.

3. In a machine for making concrete staves, comprising a foundation, a frame, and mold members mounted on the frame for forming the sides and ends of the staves, and movable selectively to position for forming the staves and to position to permit removing the staves, a pallet supporting platform, vertically adjustable means for pivotally supporting the rear end of the platform on the frame, means for moving the platform selectively to horizontal position and to inclined position, and means for forming a rigid connection between the foundation and the platform when the latter is in horizontal position.

4. In a machine for making concrete staves, comprising a foundation, a frame, and mold members mounted on the frame for forming the sides and ends of the staves, and movable selectively to position for forming the staves and to position to permit removing the staves, a pallet supporting platform, vertically adjustable means for pivotally supporting the rear end of the platform on the frame, vertically adjustable means for moving the platform selectively

to horizontal position and to inclined position, and means for forming a rigid connection between the foundation and the platform when the latter is in horizontal position.

5. In a machine for making concrete staves, comprising a foundation, a frame, and mold members mounted on the frame for forming the sides and ends of the staves, and movable selectively to position for forming the staves and to position to permit removing the staves, a pallet supporting platform, means for pivotally supporting the rear end of the platform on the frame, means for moving the platform selectively to horizontal position and to inclined position, a strip of somewhat flexible material extended across the frame and adapted to rest on the foundation, and adjustable supporting means extended between the strip and the platform adjacent to the mold members, adapted when in one position to form a rigid support between the foundation and the platform.

6. In a machine for making concrete staves, comprising a foundation, a frame, and mold members mounted on the frame for forming the sides and ends of the staves, and movable selectively to position for forming the staves and to position to permit removing the staves, a pallet supporting platform, means for pivotally supporting the rear end of the platform on the frame, means for moving the platform selectively to horizontal position and to inclined position, and means carried by the frame for forming a rigid connection between the foundation and the platform when the latter is in horizontal position.

7. In a machine for making concrete staves, comprising a foundation, a frame, and mold members mounted on the frame for forming the sides and ends of the staves, and movable selectively to position for forming the staves and to position to permit removing the staves, a pallet supporting platform, means for pivotally supporting the rear end of the platform on the frame, means for moving the platform selectively to horizontal position and to inclined position, a strip of somewhat flexible material extended across the frame and adapted to rest on the foundation, toggle levers extended between said strip and the platform, and means for moving the levers into alignment when the platform is in horizontal position.

8. In a cement stave machine, a foundation, a substantially rectangular frame, mold members slidably mounted on the top thereof, adapted to form the sides and ends of the stave, means for selectively moving said members to position to form the staves and to position to permit the formed staves to be removed from the machine, independ-

ent means for locking said members from movement relative to the frame when in position for forming the stave, a pair of spaced, parallel, rigid pallet supporting
5 members, means for pivoting the rear ends of said supporting members in horizontal alinement to the rear upper portion of the frame, a pair of toggle levers mounted adjacent to the front portion of the frame and operatively connected with the front ends of said supporting members to move the latter from horizontal to inclined position, the parts being so arranged that the levers have their pivot axes in alinement when the
10 15 supporting members are horizontal, means for mounting a pallet on said supporting members, a somewhat flexible strip of material extended across the bottom of the frame and adapted to rest on the foundation
20 25, a second pair of similarly arranged toggle levers having one end pivoted to said strip and the other end operatively connected with said supporting members, and means for simultaneously operating both pairs of toggle levers.

25 both pairs of toggle levers.

9. In a cement stave machine, a foundation, a substantially rectangular frame, mold members, slidably mounted on the top thereof, adapted to form the sides and ends of the stave, means for selectively moving said members to position to form the staves and to position to permit the formed staves to be removed from the machine, a pair of spaced, parallel, rigid pallet supporting members, means for pivoting the rear ends of said supporting members in horizontal alinement to the rear upper portion of the frame, a pair of toggle levers mounted adjacent to the front portion of the frame and operatively connected with the front ends of said supporting members to move the latter from horizontal to inclined position, the parts being so arranged that the levers have their pivot axes in alinement when the supporting members are horizontal, means for mounting a pallet on said supporting members, a somewhat flexible strip of material extended across the bottom of the frame and adapted to rest on the foundation, a second pair of similarly arranged toggle levers having one end pivoted to said strip and the other end operatively connected with said supporting members, and means for simultaneously operating both pairs of toggle levers.

55 levers.

10. In a cement stave machine, a foundation, a substantially rectangular frame, mold members slidably mounted on the top thereof, adapted to form the sides and ends
60 of the stave, means for selectively moving said members to position to form the staves and to position to permit the formed staves to be removed from the machine, independent means for locking said members from
65 movement relative to the frame when in po-

sition for forming the stave, a pallet supporting platform, a pallet stop, means for adjusting the position of the stop on the platform, vertically adjustable means for pivoting the platform to the upper rear portion of the frame, and a pair of toggle levers mounted adjacent to the front portion of the frame and operatively connected to the platform to move the latter to horizontal and inclined position, the parts being so arranged that the axes of the pivots of the levers lie in the same plane when the platform is in horizontal position. 70 75

11. In a cement stave machine, a foundation, a substantially rectangular frame, 80 mold members slidably mounted on the top thereof, adapted to form the sides and ends of the stave, means for selectively moving said members to position to form the staves and to position to permit the formed staves 85 to be removed from the machine, independent means for locking said members from movement relative to the frame when in position for forming the stave, a pallet supporting platform, vertically adjustable 90 means for pivoting the platform to the upper rear portion of the frame, and a pair of toggle levers mounted adjacent to the front portion of the frame and operatively connected to the platform to move the latter to 95 horizontal and inclined position, the parts being so arranged that the axes of the pivots of the levers lie in the same plane when the platform is in horizontal position. .

12. In a cement stave machine, a foundation, a substantially rectangular frame, mold members slidably mounted on the top thereof, adapted to form the sides and ends of the stave, means for selectively moving said members to position to form the staves and to position to permit the formed staves to be removed from the machine, independent means for locking said members from movement relative to the frame when in position for forming the stave, a pallet supporting platform, means for pivoting the platform to the upper rear portion of the frame, and a pair of toggle levers mounted adjacent to the front portion of the frame and operatively connected to the platform to move the latter to horizontal and inclined position, the parts being so arranged that the axes of the pivots of the levers lie in the same plane when the platform is in horizontal position. 100

13. In a cement stave machine, a foundation, a substantially rectangular frame, mold members slidably mounted on the top thereof, adapted to form the sides and ends of the stave, means for selectively moving said members to position to form the staves and to position to permit the formed staves to be removed from the machine, independent means for locking said members from movement relative to the frame when in position.

sition for forming the stave, a pallet supporting platform, vertically adjustable means for pivoting the platform to the upper rear portion of the frame, a pair of toggle levers mounted adjacent to the front portion of the frame and operatively connected to the platform to move the latter to horizontal and inclined position, the parts being so arranged that the axes of the pivots 5 of the levers lie in the same plane when the platform is in horizontal position, and means for adjusting the operative connection of the levers to the platform to vary the relative vertical position of the platform 10 in any of the positions of the levers.

14. In a cement stave machine, a foundation, a substantially rectangular frame, mold members slidably mounted on the top thereof, adapted to form the sides and ends 20 of the stave, means for selectively moving said members to position to form the staves and to position to permit the formed staves to be removed from the machine, independent means for locking said members from 25 movement relative to the frame when in position for forming the stave, a pallet supporting platform, means for moving said platform to selectively horizontal and to inclined position, and yielding means for securing said last described means to the 30 frame, whereby said last described means may form a rigid brace between the foundation and the platform.

15. In a cement stave machine comprising 35 a frame, and a pallet platform adjacent to the upper portion thereof, adapted to be moved selectively to inclined and horizontal position to respectively discharge and form the stave, a pair of spaced parallel 40 transverse mold members adapted to form the sides of the stave, mounted on the top of the frame and adapted to slide freely in horizontal planes, mold members adapted to form the ends of the staves extended from 45 each of said members toward the other, and a pair of spaced parallel levers pivoted midway between the side mold members to the frame, and having each end pivoted to one of said mold members, whereby pivotal movement of said levers may move the mold 50 members toward and from each other.

16. In a cement stave machine comprising a frame, and a pallet platform adjacent to the upper portion thereof, adapted to be 55 moved selectively to inclined and horizontal position to respectively discharge and form the stave, a pair of spaced parallel transverse mold members adapted to form the sides of the stave, mounted on the top 60 of the frame and adapted to slide freely in horizontal planes, mold members adapted to form the ends of the staves extended from each of said members toward the other, a pair of spaced parallel levers pivoted midway between the side mold members to the

frame and having slots at each end thereof, a pin extended from said mold members through each of said slots, and guide devices adapted to positively cause the mold members to move in parallel lines for a pre- 70 determined distance when the levers are operated to move the mold members toward and from each other.

17. In a cement stave machine comprising 75 a frame, and a pallet platform adjacent to the upper portion thereof adapted to be moved selectively to inclined and horizontal position to respectively discharge and form the stave, a pair of spaced parallel transverse mold members adapted to form the 80 sides of the stave, mounted on the top of the frame and adapted to slide freely in horizontal planes, mold members adapted to form the ends of the staves extended from each of said members toward the other, a pair of spaced parallel levers pivoted midway between the side mold members to the 85 frame and having slots at each end thereof, a pin extended from said mold members through each of said slots, cam faces formed 90 on said mold members, rollers mounted on the frame, and means for yieldingly holding the cam faces in contact with the rollers, the parts being so arranged that pivotal movement of the levers moves the mold 95 members a predetermined distance in parallel lines when the latter are adjacent to position for forming a stave, and selectively toward and from each other during the balance of the movement of the levers. 100

18. In a cement stave machine comprising 105 a frame, and a pallet platform adjacent to the upper portion thereof, adapted to be moved selectively to inclined and horizontal position to respectively discharge and form the stave, a pair of spaced parallel transverse mold members adapted to form the sides of the stave, mounted on the top of the frame and adapted to slide freely in horizontal planes, mold members adapted to form the 110 ends of the staves extended from each of said members toward the other, means for moving the mold members toward and from each other, and positive means for moving said mold members in parallel lines when they are 115 spaced apart a predetermined distance.

19. In a cement stave machine comprising 120 a frame, and a pallet platform adjacent to the upper portion thereof, adapted to be moved selectively to inclined and horizontal position to respectively discharge and form the stave, a pair of spaced parallel transverse mold members adapted to form the sides of the stave, mounted on the top of the frame and adapted to slide freely in horizontal 125 planes, mold members adapted to form the ends of the staves extended from each of said members toward the other, means for moving the mold members toward and from each other, positive means for moving said mold 130

members in parallel lines when they are spaced apart a predetermined distance, and independent means for locking said mold members in position for forming the staves.

5 20. In a cement stave machine comprising a frame, and a pallet platform adjacent to the upper portion thereof, adapted to be moved selectively to inclined and horizontal position to respectively discharge and form the stave, a pair of spaced parallel transverse mold members adapted to form the sides of the stave, mounted on the top of the frame and adapted to slide freely in horizontal planes, mold members adapted to 10 form the ends of the staves extended from each of said members toward the other, a pair of spaced parallel levers pivoted midway between the side mold members to the frame and having slots at each end thereof, 15 a pin extended from said mold members through each of said slots, cam faces formed on said mold members, rollers mounted on the frame, means for yieldingly holding the cam faces in contact with the rollers, the 20 parts being so arranged that pivotal movement of the levers moves the mold members a predetermined distance in parallel lines when the latter are adjacent to position for forming a stave, and selectively toward and 25 from each other during the balance of the movement of the levers, locking devices mounted on the frame, and means for bringing said locking devices into engagement with the mold members to bring said mem-

bers into position for forming a stave and 35 to hold said members from movement relative to each other.

21. In a cement stave machine comprising a frame and a pallet supporting platform adjacent to the upper portion thereof, adapted 40 to be moved selectively to inclined and horizontal position to respectively discharge and form a stave, a pair of spaced parallel mold members adapted to form the sides of the stave and mounted to slide freely in a horizontal plane, said members having spaced 45 openings therein, mold members adapted to form the ends of the stave extended from each of the first described members toward the other, means for moving said side members toward and from each other, said last described means being also adapted to move said members in parallel lines during a portion of their movement, strips secured to the frame adjacent to the mold members and 50 having openings therein adapted to register with the openings in the mold members when the latter are in position to form a stave, pins slidably mounted in the last described 55 openings and having tapered ends adapted to enter the openings in the mold members, and means for forcing the tapered ends of said pins into said openings, whereby the pins may move the mold members to position and lock them from movement.

Des Moines, Iowa, April 9, 1919.
